MEASURING CONTAINER FOR PEDIATRIC SOLUTION ADMINISTRATION

Robert Lewis Giles, Mundelein, Ill., assignor to
Abbott Laboratories, North Chicago, Ill.

Filed Mar. 30, 1970, Ser. No. 22,108

Term of patent 14 years

Int. Cl. D24—05; D9—01

U.S. Cl. D83—8

FIG. 2

FIG. 1

FIG. 3

FIG. 4

FIG. 1 is a side elevation of a measuring container for pediatric solution administration showing my new design; FIG. 2 is a top plan thereof;

FIG. 3 is a side elevation thereof with the measuring container for pediatric solution administration positioned for use;

FIG. 4 is a bottom elevation thereof.

The broken lines are shown for illustrative purposes only.

I claim:

The ornamental design for a measuring container for pediatric solution administration, substantially as shown and described.
